UNITED STATES PATENT OFFICE.

WILLIAM H. DURANT, OF CONCORD, NEW HAMPSHIRE.

BRAKE MECHANISM FOR CARS.

976,991.

Specification of Letters Patent. Patented Nov. 29, 1910.

Application filed July 13, 1910. Serial No. 571,686.

To all whom it may concern:

Be it known that I, WILLIAM H. DURANT, a citizen of the United States, and resident of Concord, county of Merrimack, State of New Hampshire, have invented an Improvement in Brake Mechanism for Cars, of which the following description, in connection with the accompanying drawing, is a specification, like characters on the drawing representing like parts.

This invention has for its object the production of novel and efficient manually governed brake mechanism particularly adapted for various types of freight and coal cars, locomotive tenders, and other railway rolling stock of a similar character.

One of the particular objects of my invention is the production of simple and positively acting means to lock and release the brake-shaft ratchet quickly and easily by the hand or foot of the brakeman, as may be most convenient, the construction and arrangement being such that any accumulation of cinders, snow, or other foreign matter can be instantly removed by a simple movement of the weighted pawl-controller.

Another of the special objects of my invention is the production of means for holding the ratchet from axial movement, so that it is always held positively in proper position, the downhold for this purpose being formed as a part of the brake-shaft plate.

The hub of the ratchet is elongated and rotatably mounted in a bearing forming a part of the said plate, and is annularly shouldered to rest upon the outer end of the bearing, the downhold coöperating with the hub between said bearing and the ratchet. Said ratchet is provided with a circularly-arranged series of radial teeth, and the pawl is moved into engagement therewith by the weighted controller when the latter is in its operative position, the pawl and its controller being fulcrumed coaxially on the brake-shaft plate.

These and other novel features of my invention will be fully described in the subjoined specification and particularly pointed out in the following claims.

Figure 1 is an end elevation of the upper part of the body of a box car with brake mechanism applied thereto embodying one form of my invention; Fig. 2 is an enlarged plan view of the brake mechanism below the

line 2—2, of Fig 3, the ratchet being omitted for the sake of clearness in illustration; Fig. 3 is an enlarged front view of the novel features of the mechanism, as shown in Fig. 1, the bearing for the ratchet-hub being in section; Fig. 4 is a left-hand side elevation of the mechanism shown in Figs. 2 and 3; Fig. 5 is a longitudinal section on the line 5—5, Fig. 2, showing details of construction of the pawl and pawl-controller.

I have chosen to illustrate my invention as applied to the top of a box car, but it will be understood that this is for purposes of illustration only, the principles of construction and operation of my novel brake mechanism making it equally well adapted for use in the various places on cars where it is common practice to locate mechanism of the same general character.

Referring to the drawing, Figs. 1 to 4, the usual vertical brake-shaft 1, having at its upper end an attached hand-wheel 2, Fig. 1, is in said figure located at the end of the box-car, indicated at A, said brake-shaft having fixedly attached to it in any suitable manner a ratchet 3, provided on its under side with radially arranged ratchet teeth 4. I have herein shown the ratchet mounted on the brake-shaft above the roof of the car, and fixed to the shaft by a set-screw 6 carried by an upwardly extended boss 5 on the ratchet. Upon the car roof is securely bolted a heavy casting 7 termed the brake-shaft plate, extending beyond the end of the car and having a vertical, tubular bearing 8, the upper edge of the bearing being slightly convexed, as at 9, Figs. 3 and 4. The ratchet 3, which is conveniently made as a casting, has an elongated depending hub 10 annularly enlarged at 11 to present an annular shoulder 12, the upper end of said enlargement being preferably beveled peripherally at 13. That part of the hub 10 below the shoulder 12 is mounted revolubly in the bearing 8, the shoulder 12 resting on the upper end of said bearing to sustain the ratchet vertically, as will be apparent, and for convenience in assembling the extreme lower end of the hub is preferably rounded over, as at 14. As the hub must be tipped when inserting its lower end in the bearing, to effect the proper coöperation of the downhold with the hub, as will be explained, the convexing of the hub end at 14 and the rounding or convexing of the upper end of

the bearing at 9 facilitates the assemblage of the parts. The brake-shaft plate 7 has two upright parallel ears 15, 16, carrying a transverse fulcrum bolt 17 held in place by a 5 nut 18, as clearly shown in Fig. 2. One of the ears, as 16, has its front end extended at an angle thereto toward the bearing 8, as at 19, and the upper portion of said extension is laterally enlarged to form a yoke-like 10 downhold 20 which projects over the bearing, as best shown in Fig. 4, and at such a height above it as to admit interposition of the enlargement 11 between the downhold and the top of the bearing. When the 15 ratchet hub 10 is seated in said bearing, as shown in Fig. 4 the downhold partly embraces the hub above the enlargement 11 and overhangs the upper end thereof, to thereby positively hold the ratchet and its attached 20 parts from any lifting movement with relation to the brake-shaft plate 7, the beveled end 13 of the enlargement 11 permitting the latter to pass under the downhold 20 when the hub is straightened up as its lower end 25 slips into the bearing 8. After the ratchet has been properly positioned on the brake-shaft plate as described the brake-shaft 1 is passed through the ratchet hub and secured thereto in any suitable manner.

30 In Fig. 2 the radial dotted lines indicate the pawl-engaging faces of the ratchet teeth 4, and the relation between the pawl and such series of teeth is such that when the pawl engages a tooth it is at right angles to 35 the engaging face of the tooth, thereby getting a firm and secure locking engagement therewith.

The pawl 21 is preferably made as a forging and it is fulcrumed on the bolt 17 between the ears 15, 16, and in order that the pawl will drop by gravity out of engagement with the ratchet I fulcrum said pawl nearer its rear end, as best shown in Fig. 5.

To provide a tooth-like tip for the pawl 45 the longer end thereof can be forged to the shape shown in Fig. 5, the clearance 22 permitting the tip or point 23 to effect a firm and square engagement with a ratchet tooth throughout the depth of its radial face, as 50 will be manifest.

I provide a weighted controller to coöperate with and lift the pawl into locking position, and herein I have shown said controller as comprising a weighted body portion 55 24 provided with laterally separated and parallel prolongations or cheeks 25 joined at their forward ends by a lifter-bar 26. The cheeks 25 are oppositely apertured to receive the fulcrum bolt 17 and fit easily 60 between the ears 15, 16, and the rear portion of the pawl 21 is located between the cheeks, passing over the lifter-bar 26 and under the front part of the weighted body 65 24 of the controller, which latter is provided with a transverse stop shoulder 27. This

controller is made of metal and is most conveniently and cheaply formed as a casting.

Referring to Fig. 5 it will be seen that the preponderance of weight of the pawl 21 is between the fulcrum 17 and the tip of 70 the pawl, while the preponderance of weight of the controller is at the opposite side of said fulcrum, and such weight is great enough, when permitted to act, to lift the pawl into locking engagement with 75 the ratchet. The lifting is effected through the lifter-bar 26 of the controller, which engages the under side of the pawl a short distance beyond the fulcrum.

To render the controller inoperative its 80 weighted body 24 is thrown over toward dotted line position, Fig. 5, either by the hand or foot of the brakeman, an operation performed instantly and easily under all circumstances, and when the pressure between pawl and ratchet, due to set brakes, is relieved by a slight twist of the brake-shaft 85 the pawl drops by gravity to dotted line, inoperative position.

When the controller is thus thrown over 90 the stop shoulder 27 drops onto the upper side of the pawl forward of the fulcrum 17, and when the latter is released from the ratchet the weight of the controller is added 95 to that of the pawl to depress the latter, while the stop shoulder serves to prevent over-throw of said controller, so that the latter cannot by any possibility engage or interfere with the ratchet.

I make the radius of movement of the 100 lifter-bar 26 such that it will just clear the upper side of the plate 7 when the controller is swung about its fulcrum, so that any cinders, dirt, snow or other foreign matter 105 which may have accumulated between the ears will be thereby removed. This is an important feature, for as the space below the pawl is thus cleared every time the controller is swung from one to another position there is no chance of interference with the disengaging movement of the pawl away from the ratchet.

The rear end of the pawl is rounded or 110 convexed at 28 to enable the pawl to be thrown up easily into operative position by direct pressure of the foot of the brakeman, and when this is done the pawl acts through the stop-shoulder 27 to swing the controller into full line position, Fig. 5.

It will be apparent that whenever the controller is in operative position, shown in 115 full lines, Fig. 5, the pawl will be held with its tip or toothed end 23 in position to coöperate with the ratchet and lock the same, but when said controller is in its inoperative, dotted line position, the pawl will drop away from the ratchet when pressure 120 between them is relieved.

Movement of the controller from one position to the other can be effected by a kick 125 130

of the brakeman's foot, so that no time is lost in stooping over or fumbling with the parts to put the mechanism in the desired condition.

5 The mechanism embodying my invention may be mounted on the usual step B, Fig. 1, or at the end of a flat car, as the particular location on the car is of no moment. The pawl moves in a path parallel to a plane 10 tangent to the ratchet at the outer end of the radial face of the tooth engaged by the pawl, insuring always a firm and rigid locking action and the downhold prevents any lifting of the ratchet, entirely independently 15 of the brake-shaft.

Should the pawl stick in its operative position it can be forcibly depressed by striking the controller body 24 a blow with the hand or foot, such action being transmitted 20 through the shoulder 27 to the pawl in front of the fulcrum 17. A single bolt serves as the fulcrum for the pawl and the controller, simplifying construction and effecting a 25 positive, and accurate and sure coöperation at all times between said pawl and controller.

If the brake-shaft plate 7 is mounted on a substantially horizontal surface, as for instance on the step of a box car, the bottom of 30 the plate will of course be flat, to correspond, but when the plate is located on the sloping roof of a box car, as herein illustrated, the bottom of the plate must be correspondingly sloped. Herein I provide for 35 this by forming sloping ribs 29 on the under side of the plate, the inclined under faces of such ribs corresponding to the slope of the car roof. This construction is very convenient, for if the plate is to be used on a 40 level surface all that is necessary is to remove the rib portions of the pattern from which the mold for the plate is made, and thereby the plate itself is standardized.

Changes or modifications in various details of construction and arrangement may 45 be made by those skilled in the art without departing from the spirit and scope of my invention as set forth in the claims annexed hereto.

50 Having fully described my invention, what I claim as new and desire to secure by Letters Patent is:—

1. The combination with a brake-shaft and a ratchet fixedly mounted thereon and 55 having a circularly-arranged series of teeth, of a pivotally mounted pawl to coöperate with said teeth and lock the ratchet, a weighted pawl-controller to coöperate with and lift the pawl into engagement with the 60 ratchet, and a common fulcrum for the pawl and its controller.

2. The combination with a brake-shaft and a ratchet fixedly mounted thereon and 65 having a circularly-arranged series of radial teeth, of a pivotally mounted pawl to co-

operate with said teeth at right angles thereto and lock the ratchet, a pawl-controller adapted to engage the under side of the pawl in front of its fulcrum and having a weighted body extended behind the fulcrum, 70 to lift said pawl into operative position, a common fulcrum for said pawl and the controller, and a stop shoulder on the controller to engage the top of the pawl and limit swinging movement of the controller in one 75 direction.

3. The combination with a brake-shaft and a ratchet fixedly mounted thereon and having a circularly-arranged series of teeth, of a pivotally mounted pawl to coöperate 80 with said teeth and lock the ratchet, a pawl-controller bifurcated to embrace the pawl and engaging the underside thereof in front of its fulcrum, said controller having a weighted body extended over the rear end 85 of the pawl, said controller serving to lift the pawl to coöperate with the ratchet, and a common fulcrum for the pawl and its controller.

4. The combination with a brake-shaft 90 and a ratchet fixedly mounted thereon and having a circularly-arranged series of teeth, of a pivotally mounted pawl to coöperate with said teeth and lock the ratchet, a fixed fulcrum for the pawl, near its rear end, and 95 a pawl-controller pivotally mounted on said fulcrum and engaging the underside of the pawl in front of its fulcrum, said controller having a weighted body extended above the pawl behind the fulcrum, the weight of the 100 body causing the controller when operative to lift the pawl into engagement with the ratchet.

5. The combination with a brake-shaft, and a ratchet fixed thereon and having a 105 circularly-arranged series of teeth, of a pivotally mounted pawl having its heavier end between its fulcrum and its tip, a swinging controller engaging the underside of the heavier end of the pawl and having a 110 weighted body extended rearward, to lift the pawl into locking engagement with the ratchet teeth, and means on the controller to coöperate with the upper side of the pawl and limit movement of the controller 115 to inoperative position.

6. The combination with a brake-shaft and a ratchet fixedly mounted thereon and having a circularly-arranged series of teeth, of a pivotally mounted pawl to coöperate 120 with said teeth and lock the ratchet, a pawl-controller comprising a weighted body, laterally separated cheeks to receive the pawl between them, a lifter-bar connecting the cheeks beneath the pawl in front of its fulcrum, a brake-shaft plate, ears projecting therefrom between which the pawl and its controller are mounted, and a common fulcrum for the pawl and the controller, carried by the ears, swinging movement of the 125 130

controller causing the lifter-bar thereof to clear the plate of obstructions between the ears.

7. The combination, with a brake-shaft plate having a tubular bearing, of a ratchet having an elongated hub provided with an annular enlargement, the portion of the hub beyond said enlargement being rotatably mounted in said bearing, and a downhold on said plate overhanging the outer end of the enlargement, to prevent axial movement of the ratchet away from the plate, the inner end of said enlargement resting on the adjacent end of said bearing to position the ratchet and limit movement thereof toward the plate.

8. The combination, with a brake-shaft plate having an upright tubular bearing, of a ratchet having a depending hub the lower end of which is rotatably mounted in the bearing, an annular enlargement on said hub above the bearing, a downhold on the plate partially embracing the hub above the enlargement and overhanging the latter, to prevent lifting of the ratchet, a pawl to co-operate with the ratchet, a swinging pawl-controller movable to elevate or depress the pawl, upright ears on the plate, between which the pawl and controller are positioned, and a common fulcrum for said parts carried by the ears.

9. The combination, with a brake-shaft plate having a tubular bearing, of a ratchet having a hub rotatably mounted in said bearing, means on the plate to co-operate with said hub and prevent axial movement of the ratchet away from the plate, and an annular shoulder on the hub seated on the outer end of said bearing to prevent move-

ment of the ratchet and its hub toward the plate.

10. The combination, with a brake-shaft plate having an upright tubular bearing, and a yoke-like downhold projecting over the bearing, of a ratchet having a depending hub rotatably mounted in said bearing, said hub having an annular enlargement between the bearing and the downhold, to rest upon the top of the former and extend under the latter, whereby the ratchet is positively held from vertical movement, a pawl to co-operate with the ratchet, a weighted controller for the pawl, and a common fulcrum for said pawl and controller, fixedly mounted on the brake-shaft plate.

11. The combination with a vertical brake-shaft and a ratchet fixedly mounted thereon, said ratchet having radial teeth on its under side and a depending hub, of a pawl to co-operate with said teeth at right angles thereto and lock the ratchet, a pawl-controller adapted to engage the under side of the pawl in front of its fulcrum and having a weighted body extended behind the fulcrum, to lift said pawl to operative position, a brake-shaft plate having an upright tubular bearing for the ratchet hub, a downhold on said plate to co-operate with said hub and prevent lifting of the ratchet, and a common fulcrum for the pawl and its controller, mounted on said plate.

In testimony whereof, I have signed my name to this specification, in the presence of two subscribing witnesses.

WILLIAM H. DURANT.
